UNITED STATES PATENT OFFICE.

LEON B. STODDARD, OF BAKER, OREGON.

LOOSE-LEAF BINDER.

1,401,566.

Specification of Letters Patent. Patented Dec. 27, 1921.

Application filed August 12, 1919. Serial No. 317,086.

To all whom it may concern:

Be it known that I, LEON B. STODDARD, a citizen of the United States, residing at Baker, in the county of Baker and State of Oregon, have invented certain new and useful Improvements in Loose-Leaf Binders, of which the following is a specification.

This invention relates to a binder for loose leaf records, tariff files, maps, etc., and 10 an object of the invention is to provide a binder of this nature which will bind sheets provided with openings or slots punched near one edge. In making up loose leaves for various types of records, some are provided with holes or perforations near one 15 edge, while others are provided with various forms of slots, and each leaf having the distinctive type of opening therein is designed for use with a particular type of 20 binder which sometimes results in considerable inconvenience to the user, owing to the failure to have the proper type of binder, and an object of this invention is to provide a binder of the spur type, which 25 will effectively bind leaves provided with various types of perforation.

Another object of the invention is to provide a binder as specified which comprises a pair of hingedly connected sections, each 30 carrying, at its free edge, a plurality of arcuate spurs adapted for seating in recesses in the other or companion section, and the spurs upon one section are disposed staggeredly to the spurs upon the other section 35 to permit the entire closing of the sections if desired, and also to provide binder strips having convex outer surfaces along the free edges of the hinged members, which strips are adapted to form line binding contact 40 with the leaves to securely bind them in the back or binder.

A further object of this invention is to provide a simple and efficient form of locking mechanism for locking the hinged sections in leaf binding position, the said lock 45 comprising an arcuate segment carried by one section and provided with ratchet teeth on its concaved surface, which ratchet teeth are adapted for engagement with companion 50 ratchet teeth formed upon the convex upper surface of a locking lug, to lock the sections in various adjusted positions, and further to mount the said locking lug upon a flat spring, which normally urges the lug into 55 locking position with respect to the segments, and which permits depression of the

locking lug to release the locking engagement with the segment.

A still further object of this invention is to provide the locking ratchet teeth upon the lug at an angle, and to adjustably support this locking lug providing adjustable connection with its operating pin to permit longitudinal movement of the lug to vary the pressure of the teeth thereon with the 60 teeth of the locking segments, and to compensate for wear upon these locking teeth.

Other objects of the invention will appear in the following detailed description taken in connection with the accompanying drawings, forming a part of this specification, and in which drawings:

Figure 1 is a plan view looking into the binder in an open position.

Fig. 2 is a cross section taken on the line 75 2-2 of Fig. 1.

Fig. 3 is a fragmentary longitudinal section through the binder illustrating the locking lug and its operating pin.

Fig. 4 is a cross section through the binder 80 similar to Fig. 3 only showing the sections partly closed.

Fig. 5 is a detail perspective view of the locking lug, and

Fig. 6 is a detail perspective view of the 85 locking segment which coacts with the said locking lugs.

Referring more particularly to the drawings, wherein like characters indicate like 90 and corresponding parts throughout the several views, the two sections 10 and 11 of the binder are hingedly connected by means of hinges 12, and they have rounded outer surfaces, to present an artistic appearance, as well as to prevent the provision of corners 95 thereon. The hinged sections 10 and 11 have facing portions thereof cut away to accommodate the locking construction. However, a portion of their facing sides as indicated at 13 is adapted for facial abutment when the sections are completely closed. Outwardly of these portions 13, the inner facing portions of the sections are cut away to accommodate or receive the loose leaves to be bound by the device. The sections 10 and 11 are preferably covered with any suitable 100 type of fabric as indicated at 14 which fabric also serves to connect the covers 15 to the sections 10 and 11 as clearly shown in Figs. 2 and 4 of the drawings. Along the inner 105 surface of each of the sections 10 and 11 near its outer edge is positioned a binding bar 16,

- preferably of metal, and presenting a convex surface for engagement with the leaves to be bound by the binder so as to provide line binding engagement with a leaf. These strips 16 carry arcuate spurs 17, the spurs upon one strip being disposed staggeredly with respect to the spurs upon the other strip as clearly shown in Fig. 1 of the drawings. The strips 16 and also the sections 10 and 11 are provided with openings 18 therein which are adapted to receive the spurs 17 of the other sections when the sections are partly or wholly closed. The outer ends of the spurs 17 are preferably sharpened as shown at 18' and are adapted to extend through the perforations or openings along the leaves to be bound by the binder, or if desired, they can, owing to their sharpened ends 18 be used as perforators for perforating the leaves to permit their attachment to the binder. Means for locking the sections 10 and 11 in partially or wholly closed position against accidental outward movement is provided, and it comprises a segment 20 which is carried by the section 10, being attached thereto through the medium of an attaching plate 21. The segment 20 is provided with ratchet teeth 22, on its concaved or under surface, which teeth are adapted to coact with the ratchet teeth 23, formed upon the upper arcuate end of the locking lug 24. The locking lug is mounted upon the threaded end 25 of an operating pin 26 and it is held against rotation by engagement with the upstanding sides 27 of a U-shaped member 28 carried by the section 11. The operating pin 26 is rotatably carried by the upturned end 29 of a flat spring 30, and an upstanding bracket 31 carried by the said flat spring so as to form a yieldable support for the locking lug 24 to normally urge it outwardly for locking engagement between the teeth 23 thereof and the teeth 22 of the segment 20. The teeth 22 and 23 are positioned at oblique angles, as clearly shown in the drawings, in order to provide a firm binding engagement of the segment 20 in various positions with respect to the locking lug or block 24 by rotation of the operating stem 26 and consequential adjustment of said locking lug 24. This arrangement of teeth will likewise compensate for wear thereupon and prevent any loose playing or loss of effective relation between the sections 10 and 11. The spring 30 normally urges the locking lug 24 outwardly and when the sections are in binding position as shown in Fig. 4 to release the lock structure to permit the opening of the binder, the stem 26 is depressed or moved downwardly, which moves the lock 24 downwardly therewith owing to the yieldable mounting of the block upon the spring 30 to disengage the teeth 23 and the teeth 22 and then allow the sections 10 and 11 to be opened or moved apart. A suitable stop 34, preferably a staple, is provided, to limit the outward movement of the stem 26 and consequently of the block 24 under action of the flat spring 30. The section 11 is provided with an arcuate recess 35 which receives the segment 20 when the sections 10 and 11 are in closed position or receives part of the segment when the sections are only partly closed. A suitable knurled head 36 is carried by the outer end of the pin or stem 26 to facilitate its rotation and operation, and the sections 10 and 11 are cut away, as shown at 37 at their ends at which the head 36 is positioned to permit the insertion of an operator's fingers between the sections 10 and 11 to operate the lock structure.
- As the binder becomes filled with pages, records, or the like, the lugs 24 can be adjusted upon various parts of the segment 20, to accommodate the expansion incident thereto.
- Changes in details may be made without departing from the spirit of this invention, but;
- I claim:
1. In a loose leaf binder, the combination of a pair of hingedly connected sections, an arcuate segment carried by one section and provided with ratchet teeth on its concaved surface, and a yieldably mounted locking block carried by the other section and having ratchet teeth thereon adapted to engage with the ratchet teeth of the segments to lock the sections in adjusted positions. 90
  2. In a loose leaf binder, the combination of a pair of hingedly connected sections, an arcuate segment carried by one section and provided with ratchet teeth on its concaved surface, a yieldably mounted locking block carried by the other section and having ratchet teeth thereon adapted to engage with the ratchet teeth of the segments to lock the sections in adjusted positions, the teeth upon said block and segments being disposed in oblique angles to the lines of the segments and block, and means for adjusting the position of said block to cause a firm binding engagement of the teeth. 105
  3. In a loose leaf binder, the combination of a pair of hingedly connected sections, leaf binding means carried by said sections, a segment carried by one of said sections and provided with ratchet teeth on a concaved surface, a flat spring carried by the other section, a locking block supported upon said flat spring and provided with ratchet teeth on its outer surface for meshing with the segment carried ratchet teeth, said spring normally urging said block outwardly for locking engagement with the segment, and a stem connected to said block to permit depression of the block for releasing its engagement with the segment. 115
  4. In a loose leaf binder, the combination of a pair of hingedly connected sections, leaf 120
  5. In a loose leaf binder, the combination of a pair of hingedly connected sections, leaf 125

- binding means carried by said sections, a segment carried by one of said sections and provided with ratchet teeth on a concaved surface, a flat spring carried by the other section, a locking block supported upon said flat spring and provided with ratchet teeth on its outer surface for meshing with the segment carried ratchet teeth, said spring normally urging said block outwardly for locking engagement with the segment, a stem connected to said block to permit depression of the block for releasing its engagement with the segment, the ratchet teeth upon said block being disposed at an oblique angle to the lines of the block, said block adjustably mounted upon its operating stem to permit adjustment longitudinally thereon for varying the clamping engagement of the ratchet teeth of the block with the teeth of said segment. 5
5. In a loose leaf binder, the combination of a pair of hingedly connected sections, binding strips mounted on the inner facing surfaces of the free edges of said sections and presenting convex surfaces for binding engagement with loose leaves, a segment carried by one of said sections and provided with ratchet teeth thereon, a flat spring carried by the other section, a stem rotatably supported by said flat spring, a locking block adjustably mounted upon said stem and provided with an arcuate outer surface, ratchet teeth upon said arcuate surface and adapted for locking engagement with the ratchet teeth upon said segment, said spring normally urging said locking block into locking engagement with the segments, means for engaging said operating stem to limit the movement of the block under action of said spring, 10 a plurality of arcuate spurs carried by said binding strip, the spurs upon one strip disposed staggeredly with respect to the spurs upon the other strip, said strips and sections being provided with recesses adapted to receive said spurs therein when the sections are in binding positions, a binder positioned about the outer surfaces of said sections, and covers connected to said sections by said binder. 15
6. In a loose leaf binder, the combination of a pair of hingedly connected sections, binding strips mounted on the inner facing surfaces of the free edges of said sections and presenting convex surfaces for binding engagement with loose leaves, a segment carried by one of said sections and provided with ratchet teeth thereon, a flat spring carried by the other section, a stem rotatably supported by said flat spring, a locking block adjustably mounted upon said stem and provided with an arcuate outer surface, ratchet teeth upon said arcuate surface and adapted 20
- for locking engagement with the ratchet teeth upon said segment, said spring normally urging said locking block into locking engagement with the segments, and means for engaging said operating stem to limit the movement of the block under action of said spring. 25
7. In a loose leaf binder, the combination of a pair of hingedly connected sections, binding strips mounted on the inner facing surfaces of the free edges of said sections and presenting convex surfaces for binding engagement with loose leaves, a segment carried by one of said sections and provided with ratchet teeth thereon, a flat spring carried by the other section, a stem rotatably supported by said flat spring, a locking block adjustably mounted upon said stem and provided with an arcuate outer surface, ratchet teeth upon said arcuate surface and adapted for locking engagement with the ratchet teeth upon said segment, said spring normally urging said locking block into locking engagement with the segments, means for engaging said operating stem to limit the movement of the block under action of said spring, 30 a plurality of arcuate spurs carried by said binding strip, the spurs upon one strip disposed staggeredly with respect to the spurs upon the other strip, said strips and sections being provided with recesses adapted to receive said spurs therein when the sections are in binding positions, a binder positioned about the outer surfaces of said sections, and covers connected to said sections by said binder. 35
8. In a loose leaf binder, the combination of a pair of hingedly connected sections, a rack carried by one of said sections, having teeth thereon, a locking block carried by the other section, and having teeth thereon adapted to engage with the teeth upon the rack for holding the sections in a predetermined position, and means for advancing or retracting said locking block to compensate for wear upon the teeth thereof by the rack teeth. 40
